UNITED STATES PATENT OFFICE.

GEORGE E. MARLATT, OF ALLEGHENY, PENNSYLVANIA.

MECHANISM FOR THROWING LINES OF MATRICES INTO LINOTYPE-MACHINES.

No. 845,807.

Specification of Letters Patent.

Patented Feb. 26, 1907.

Application filed February 1, 1906. Serial No. 298,933.

To all whom it may concern:

Be it known that I, GEORGE E. MARLATT, of Allegheny, in the county of Allegheny and State of Pennsylvania, have invented an improvement in Mechanism for Throwing Lines of Matrices into Linotype-Machines, of which the following is a full, clear, and exact description, reference being had to the accompanying drawings, forming part of this specification, in which—

Figure 1 is an elevation of a portion of a linotype-machine, showing my invention applied thereto. Fig. 2 is a side elevation of the keyboard, showing the application of my invention. Fig. 3 is a rear end elevation of the device employed by me. Fig. 4 is a plan view of the same. Fig. 5 is a vertical sectional view on the line V V of Fig. 4, and Fig. 6 is a vertical cross-sectional view on the line VI VI of Fig. 4.

Like symbols of reference indicate like parts wherever they occur.

My invention relates to an improvement in linotype-machines; and it consists in devices connected with the power mechanism and adapted to operate the assembling-elevator.

I will now describe my invention so that others skilled in the art may manufacture and use the same.

In the drawings, 2 represents the keyboard-shaft, which I employ as the power-shaft of my improved mechanism. Keyed to the end of the shaft 2 is the gear-wheel 3, and fitting on the keyboard rubber-roll-shaft bracket is a bracket 4, which is secured to the collar of the rubber-roll-shaft bracket by means of a split hub or yoke 5. Extending through the bracket 4 on a line parallel to the shaft 2 is a shaft 6, loosely mounted on which is a gear-wheel 7, which meshes with the gear-wheel 3. The gear-wheel 7 is prevented from moving longitudinally on the shaft 6 by means of a hub 8 and a screw 9, projecting through the hub and into an annular groove 10 in the shaft 6.

Mounted loosely on the shaft 6 is a pinion 11, having a hub 12, which is journaled in the arm 4' of the bracket 4 and is prevented from moving longitudinally with the shaft 6 by means of a screw 13 passing through the journal 4' into an annular groove 14 in the hub 12.

On the outer face of the gear-wheel 7 and the inner face of the pinion 11 is a clutch 15,

the parts of which are adapted to be joined by the longitudinal movement of the shaft 6. This movement is imparted to the gear-wheel 7 by means of the spring 16, which encircles the shaft 6 between the nuts 17 and 18, the washer 18, which bears against the journal-box 4'. This spring tends to keep the parts of the clutch normally in contact with each other, and as the gear-wheels 3 and 7 rotate continually during the operation of the linotype-machine the pinion 11 is caused to rotate so long as the two parts of the clutch 15 are in contact with each other.

On the inner end of the shaft 6 is a collar 19, which when the clutch 15 is united bears against the face of the bracket 4. When, however, the shaft 6 is so moved as to separate the parts of the clutch, a space or recess exists between the collar and the bracket, into which the spring trigger-arm 20, under the force of the spring 21, immediately enters. This trigger-arm 20 is an extension of the key-lever 22, which is provided with the keys 23 23' as an addition to the keyboard of the linotype-machine. In the drawings I have shown two keys 23 and 23', and in addition to these a knee-lever attachment 24 may be connected with the lever 22. The pinion 11 at all times meshes with a vertical rack 25, the upper end of which is adjustably attached to the assembling-elevator 26, which may be of the usual construction, by means of the set-screw 27. The effect of this arrangement and construction is that whenever the parts of the clutch 15 are brought together and the pinion 7 is caused to revolve the rack 25 ascends, carrying with it the assembling-elevator 26 to the desired position. At this point the line-delivery lever 28 is thrown into action in the usual manner by the operation of the linotype-machine and causes the line of matrices to be carried from the assembling-elevator to the casting position.

On the hub of the line-delivery lever is attached an adjustable trigger or lever-arm 29, which as the hub of the line-delivery lever rotates comes into contact with the projecting end of the shaft 6 and forces the same against the action of the spring 16 to allow the trigger 20 to drop between the collar 19 and the face of the bracket 4 under the force of the spring 21. Thus the trigger-arm keeps the shaft 6 from returning to its normal position after the pin 29 has passed the end of the

shaft. This movement of the shaft 6 separates the parts of the clutch 15, releasing the pinion 11 from the gear-wheel 7 and permitting the rack 25 to descend under the weight of the assembling-elevator, the pinion rotating idly on the shaft 6. It will be noticed that the end of the rack 25 is mutilated, the teeth being removed, so that when the rack reaches the extent of the desired upward movement the pinion has no power to carry it farther, and it remains at this point until released by the action of the pin 29. When it is desired to again raise the assembling-elevator, the linotype operator by touching either of the keys 23 23' or pressing the knee-lever 24 withdraws the trigger 20, allowing the spring 16 to unite the parts of the clutch 15, which causes the elevator to ascend in the manner already described. Extending through the journal-casting 4' is an adjusting-screw 31, which bears against the back of the rack and causes it to mesh properly with the pinion 11.

In order to prevent the assembling-elevator from descending too rapidly, I employ a counterbalancing-weight 32, the cord 33 from which passes up a pulley 34, which is journaled on the frame of the machine, the other end of the cord being secured to the assembling-elevator. The counterweight 32 is of less weight than the weight of the elevator, and when the elevator-rack is released, as already described, and the elevator descends the weight 32 acts to lessen its speed.

The advantages of my invention result from the construction which enables the elevator to be raised by the mere touching of a key or lever, thus obviating the time and manual power which have heretofore been required.

Having thus described my invention, what I claim, and desire to secure by Letters Patent, is—

1. In a linotype-machine, a shaft in communication with the power mechanism of the machine, a pinion connected with said shaft, a clutch and a rack extending from the as-

sembling-elevator and gearing with the pinion; substantially as specified.

2. In a linotype-machine, the combination of the assembling-elevator, a rack connected therewith, a pinion mounted on a reciprocating shaft, a clutch by means of which the power mechanism of the linotype-machine may be thrown in and out of connection with the pinion, a trigger by means of which the clutch is held in its separated position and a device connected with the line-delivery lever adapted to throw the parts of the clutch out of connection with each other; substantially as specified.

3. In a linotype-machine the combination of an assembling-elevator, a rack connected therewith, a pinion mounted on a reciprocating shaft, a clutch by means of which the power mechanism of the linotype-machine may be thrown in and out of connection with the pinion, a trigger by means of which the clutch is held in its separated position, a lever extending from the trigger to the keyboard and provided with a key, and a device connected with the line-delivery lever and adapted to throw the parts of the clutch out of connection with each other; substantially as specified.

4. In a linotype-machine, the combination of an assembling-elevator, a rack and pinion for raising the elevator, power mechanism for driving the pinion, a clutch by means of which the power mechanism may be thrown in or out of connection with the pinion, a trigger by means of which the clutch is held in its separated position, a lever extending from the trigger to a point within reach of the operator, and a device connected with the line-delivery lever and adapted to throw the parts of the clutch out of connection with each other; substantially as specified.

In testimony whereof I have hereunto set my hand.

GEORGE E. MARLATT.
